C. G. BATES.
UNIFORM STANDARD FORM CABINET,
FILED JAN. 7, 1922.

INVENTOR.
CHARLES G. BATES.
BY
James F. Williamson
ATTORNEY

UNITED STATES PATENT OFFICE.

CHARLES G. BATES, OF MINNEAPOLIS, MINNESOTA.

UNIFORM STANDARD-FORM CABINET.

Application filed January 7, 1922. Serial No. 527,670.

To all whom it may concern:

Be it known that I, CHARLES G. BATES, a citizen of the United States, residing at Minneapolis, in the county of Hennepin and State of Minnesota, have invented certain new and useful Improvements in Uniform Standard-Form Cabinets; and I do hereby declare the following to be a full, clear, and exact description of the invention, such as will enable others skilled in the art to which it appertains to make and use the same.

This invention relates to a cabinet, particularly to a filing cabinet adapted to contain insurance or other forms. Insurance forms of standard size and design are now required in practically all States of the Union and the cabinet of the present invention is designed particularly for holding such forms and for the use of agents handling the same.

It is an object of this invention to provide a simple, convenient cabinet which will contain the forms above referred to and by means of which they can be quickly placed in position and withdrawn.

Other objects and advantages of the invention will be apparent from the following description made in connection with the accompanying drawings in which—

Fig. 1 is a top plan view of a cabinet as shown in Fig. 3;

Fig. 2 is a front elevation of the same when in closed position;

Fig. 3 is a transverse section of the cabinet with the lid thereof raised, taken on the line 3—3 of Fig. 1;

Fig. 4 is a detail on an enlarged scale of one of the hinged sections.

Referring to the drawings, the cabinet is seen to comprise a rectangular bottom portion 1, the side walls 2 and the end walls 3, which, together, form a rectangular box. A reinforcing strip 4 surrounds the front side and ends of the box. A lid member 5 having the flange strips 6 on the front and ends thereof, is hinged by a hinge 7 to the rear side wall 2 and is adapted to tightly close the cabinet when in closed position, as shown in Fig. 2. The lid member 5 is held in open position by the links 8, one of which is hinged to the inside thereof and the other of which is pivotally secured to the inside of one of the end walls 3, the

links being pivoted together, as shown in Fig. 3 and forming a toggle. This toggle when straightened with the lid open will hold the same in open position. It can be broken and disposed inside of the box when the lid is closed. The cabinet has a partition member 9 extending transversely thereacross a short distance from one end forming an end compartment 10. A partition 11 extends longitudinally of the cabinet from the partition 9 to one of the end walls 3 at substantially the transverse center thereof or slightly toward the rear end. The partition 11 is shown as received in slots in the members at the ends thereof and this partition does not extend quite to the top of the cabinet, as shown in Fig. 3. A partition member 12 extends between the partition 9 and one of the end walls 3 and is hinged at its lower portion a short distance from the rear side wall 2, the upper end of the partition extending substantially to the top of the cabinet and being beveled to a sharp edge which rests against the said side wall 2 at its upper portion. This partition forms a triangular compartment 13. Another partition member 14 is hinged at its lower end some distance from the front of the partition 11 and is of substantially the same height as the partition 11. Short spacing blocks 15 are disposed between the partitions 11 and 14 against which the latter normally rests to be retained in the position shown in Fig. 3. The partition 14 forms with the partition 11 another substantially triangular compartment 15 and forms with the front side wall 2 one of the main compartments 16, the other main compartment 17 being formed between partitions 11 and 12.

The main compartments 16 and 17 are adapted to receive the standard insurance forms, which forms are almost as long as said compartment. The rate lists and other smaller documents can be conveniently filed in the compartments 13 and 15, while the shorter forms of miscellaneous nature can be conveniently filed in the compartment 10. The cabinet has been found to have great utility in actual practice and to be most convenient and efficient for the rapid handling of the various forms, which, as stated, are now largely of a standard size as required by State laws.

It will, of course, be understood that various changes may be made in the form, details and proportions of the device without departing from the scope of applicant's invention, which, generally stated, consists in the matter shown and described and set forth in the appended claims.

What is claimed is:

1. A uniform standard form cabinet comprising a substantially rectangular box, a partition extending longitudinally thereof at substantially its transverse center, a partition extending longitudinally thereof in front of said partition, said last named partition being hinged at its lower portion and normally adapted to stand in inclined position with its upper portion nearer the first mentioned partition than its lower portion.
2. The structure set forth in claim 1, both of said partitions terminating a short distance below the top edge of the box.
3. A uniform standard form cabinet having in combination a substantially rectangular box, a partition extending transversely of said box and spaced a short distance from one end thereof, a partition extending from said first mentioned partition to the other end of the box and being hinged at its lower portion, the upper portion of the same resting against the rear side of the box.
4. A form cabinet having in combination a substantially rectangular box, a partition extending transversely of the same and spaced a short distance from one end thereof, a vertical stationary partition extending from said partition to the other end of the box at substantially the transverse center thereof, and a partition having its lower edge hinged to the bottom of the box a short distance in front of said stationary partition and normally disposed to incline towards the same.
5. The structure set forth in claim 4 both

of said last mentioned partitions terminating a short distance from the top of the box. 45

6. The structure set forth in claim 5, and a partition extending from the transverse partition to the other end of the box having its lower end hinged to the bottom of the box a short distance from the rear side thereof 50 and having its upper end normally resting against the rear side of the box.

7. The structure set forth in claim 5, and a hinged cover for said box.

8. A form cabinet having in combination a 55 substantially rectangular box, a partition extending transversely thereof adjacent one end, vertical partitions extending longitudinally thereof between said transverse partition and the other end of the box and being hinged at their lower ends to the bottom of the box, one of said partitions inclining toward the rear side of the box at its upper end, and the other inclining toward the fixed vertical partition at its upper end. 60 65

9. The structure set forth in claim 8, and a hinged cover for said box.

10. The structure set forth in claim 8, a hinged cover for said box, and means for holding said cover in open position. 70

11. A form cabinet comprising a substantially rectangular box, a partition extending transversely thereof adjacent one end, a vertical fixed partition extending from said fixed partition to the remote end of the box, 75 a hinged portion also extending from the transverse partition to the remote end of the box having its upper end normally inclined toward said fixed partition and another partition extending from said transverse partition to the remote end of the box and being inclined with its upper end in contact with the rear of the box. 80

In testimony whereof I affix my signature.

CHARLES G. BATES.
